INVENTOR
Harold W. Rambusch
BY *John F. Ryan*
ATTORNEY

UNITED STATES PATENT OFFICE

HAROLD W. RAMBUSCH, OF BROOKLYN, NEW YORK, ASSIGNOR TO RAMBUSCH DECO-RATING COMPANY, OF NEW YORK, N. Y., A CORPORATION OF NEW YORK

TABERNACLE

Application filed December 19, 1930. Serial No. 503,483.

This invention relates to the construction of a tabernacle, such as is used on the altar in a church. During certain religious ceremonies, it is desirable to have a so-called 5 throne superimposed above the tabernacle of the altar to receive the ostensorium, for instance. The rule in certain denominations is that this throne must be removable and may not be a permanent throne. Therefore, if the 10 throne space is disposed on top of the tabernacle, a removable pedestal or stool must be used to support what it is desired to expose or exhibit in the throne space.

An object of the invention is to furnish a 15 movable canopy for the tabernacle, which may be conveniently raised to form a throne and throne space.

It is another object to produce this desirable result while maintaining proper proportions and symmetry in design and without sacrificing the artistic appearance whether the canopy is in its raised or lowered position.

And still a final object of this invention is to produce a movable throne and throne 25 space, which may be converted from a simple tabernacle to a combination of tabernacle and throne with the least possible effort on the part of the operator so that the change may be quickly and expeditiously made by 30 a clergyman during the performance of a ceremony, if need be.

The characteristics and advantages of the invention are further sufficiently explained in connection with the following detailed description of the accompanying drawings, which illustrate certain representative embodiments. After considering these examples, a person skilled in the art will understand that many variations may be made 40 without departing from the principles involved, and I contemplate employment of any structures that are properly within the scope of the appended claims.

Looking at the drawings,

Fig. 1 is a front elevation, partly in section, illustrating the tabernacle with the canopy thereof in its lowered position.

Fig. 2 is a front elevation illustrating the canopy of the tabernacle in its raised position, 50 thus forming a throne.

Fig. 3 is a right section taken through 3—3 of Fig. 1.

Fig. 4 is a right section taken through 4—4 of Fig. 1.

Fig. 5 is a right section taken through 5—5 of Fig. 1.

The combined tabernacle and removable throne comprises a tabernacle portion T, furnished with the usual tabernacle doors D on the front thereof, which are shown as a pair 60 of doors adapted to swing outwardly on suitable hinges illustrated at 1 and 2 in Fig. 4. The interior of the tabernacle T shown at 3 forms the space known as the safe. The tabernacle is surmounted by a canopy C, 65 which is supported upon three vertically disposed supporting members. Two of these supporting members are in the form of hollow tubes placed at the sides of the tabernacle and illustrated at 4 and 5 respectively. The 70 third supporting member comprises a hollow tube of approximately square cross-section and is disposed at the rear of the tabernacle and illustrated at 6. The tubular supporting members 4 and 5 are adapted to enclose stationary supporting rods 7 and 8, which are of rectangular cross-section and are preferably embedded in a footing of concrete at the lowermost ends thereof, as shown at 75 10 and 11. These rods may be furnished with cross-pins shown at 12 so as to supply additional supporting area between the concrete footing and the rods.

The upper ends of these rods are notched to form a series of teeth as illustrated at 14. 85 Each of the supporting members 4 and 5 is supplied with a combined spring pressed pawl and handle shown at 15. This device comprises a tubular outer portion adapted to enclose the pawl P', a plunger attached 90 thereto, a knob K on the outer end of said plunger and a spring S normally urging said pawl inwardly. The pawl P' is designed to cooperate with the teeth 14, which are cut in the rods 7 and 8 so as to support the canopy C when in a raised position above the top of the tabernacle T. A supporting member 6, which is attached to the canopy and adapted to move up and down therewith, is 95 guided by suitable bands or straps 17, which 100

are attached to the rear wall of the tabernacle, as best shown in Figs. 1, 3 and 4. These guide straps or bands 17 form a sliding engagement with supporting member 6, allowing it to move freely up and down and yet always maintaining it in a vertical position.

Attached to the lower end of supporting member 6 are a pair of hooks 20, to which are secured ropes 21, which pass over pulleys 22 and have attached to the other ends thereof a pair of counterweights W. These counterweights may be constructed in the form of hollow receptacles, adapted to receive lead shot or other material to form a counterbalance substantially equal to the weight of the canopy C and the supporting members 4, 5 and 6.

The tabernacle is constructed to rest upon the altar top illustrated at 25, which in turn is supported by the altar A. The pulleys 22 may be attached to suitable axles 26, which may be secured to a framework 27, which is illustrated in this particular embodiment as constructed of suitable wooden cross-pieces. The top of the tabernacle T is furnished with the pedestal P which forms the pedestal of the throne.

The ornamental ring 30, which is disposed about the lowermost edge of the canopy C, is adapted to support and conceal a veil or curtain rod not shown, so that a veil or curtain may be arranged to be attached to the canopy and move up and down therewith.

In operation, a person desiring to raise the canopy C, and thus form a throne and throne space above the tabernacle T, has merely to lift the canopy C by using the handles 15. This may be readily accomplished with little effort because the canopy and its supporting members are carefully balanced by the weights W and, when it is raised to the desired height, the pawls P', cooperating with the teeth 14 on the rods 7 and 8, will serve to prevent it from traveling downwardly again until it is desired to replace it in its lowermost position, when it is only necessary to pull the knobs K outwardly and thus release the pawls P' from engagement with teeth 14. A slight downward pressure is sufficient to bring the canopy down to its original place immediately above the top of the tabernacle. The counterweights W may be so adjusted as to exactly balance the weight of the canopy and supporting members and then the inherent friction which exists between the moving parts will be sufficient to maintain the canopy in any given position so that the person raising or lowering the canopy must furnish only sufficient physical force to overcome this small force of friction.

I claim:

1. In a tabernacle, a body portion forming a safe adapted to receive sacred vessels and the like, a vertically movable canopy above said

body portion, supporting means for said canopy adapted to allow it to be raised or lowered in relation to said body portion and so disposed in relation to said canopy and body portion as to form an open space beneath the center of said canopy with unobstructed access thereto from the front of said tabernacle so that when said canopy is in its raised position it forms in cooperation with the top of said body portion a throne and throne space suitable for the exhibition of sacred articles and the like.

2. In a tabernacle, a body portion forming a safe adapted to receive sacred vessels and the like, a vertically movable canopy above said body portion, a plurality of supports for said canopy adapted to allow it to be raised or lowered in relation to said body portion and so disposed in relation to said canopy and body portion as to form an open space beneath the center of said canopy with unobstructed access thereto from the front of said tabernacle so that when said canopy is in its raised position it forms in cooperation with the top of said body portion a throne and throne space suitable for the exhibition of sacred articles and the like.

3. In a tabernacle, a body portion forming a safe adapted to receive sacred articles and the like, a vertically movable canopy above said body portion, supports for said canopy adapted to allow it to be raised or lowered in relation to said body portion, means for counterbalancing the weight of said canopy and attached parts, and means for holding said canopy in any one of a plurality of intermediate positions.

4. In a tabernacle, a body portion forming a safe adapted to receive sacred vessels and the like, a canopy over said body portion, supporting means for said canopy adapted to allow it to be raised or lowered in relation to said body portion, and a centrally disposed pedestal on said body portion adapted to receive sacred vessels and the like for exhibition thereof when said canopy is in a raised position relative to said body portion.

5. In a tabernacle, a body portion forming a safe adapted to receive sacred vessels and the like, a vertically movable canopy above said body portion, and supporting means for said canopy adapted to allow it to be readily raised or lowered and when said canopy is in the raised position adapted to form in cooperation with it and the top of said body portion a throne and throne space suitable for the exhibition of sacred vessels and the like.

6. In a tabernacle, a body portion forming a safe adapted to receive sacred vessels and the like, a vertically movable canopy above said body portion, supporting means for said canopy engaging said canopy near the outer edge thereof so that, when said canopy is raised, it will form in cooperation with the

top of said body portion a throne and throne space.

7. In a tabernacle, a body portion forming a safe adapted to receive sacred vessels and the like, a vertically movable canopy above said body portion, supporting means for said canopy adapted to allow it to be raised or lowered in relation to said body portion, means for counterbalancing the weight of said canopy and attached parts, and means for holding said canopy in any one of a plurality of intermediate positions.

8. In a tabernacle, a body portion forming a safe adapted to receive sacred vessels and the like, a vertically movable canopy above said body portion, supporting means for said canopy engaging said canopy near the outer edge thereof so that when said canopy is raised it will form in cooperation with the top of said body portion a throne and throne space, and means for counterbalancing the weight of said canopy and connected parts so that it may be readily raised and lowered.

In testimony whereof I have signed this specification this 12 day of December, 1930.

HAROLD W. RAMBUSCH.
